UNITED STATES PATENT OFFICE.

STANHOPE BOAL, OF PIQUA, OHIO.

DESIGN FOR A HEATING-STOVE.

SPECIFICATION forming part of Design No. 27,629, dated September 7, 1897.

Application filed July 19, 1897. Serial No. 645,178. Term of patent 7 years.

To all whom it may concern:

Be it known that I, STANHOPE BOAL, residing at Piqua, in the county of Miami and State of Ohio, have invented and produced a new and original Design for Heating-Stoves, of which the following is a specification.

My invention relates to a design for heating-stoves.

The leading feature of my design consists of raised scrollwork combined with a raised wavy leaf and loop work.

The features of my invention are more fully set forth in the description of the accompanying drawing, making a part of this specification, in which the figure represents a perspective elevation of a heating-stove ornamented with my design.

A represents the base-frame and legs, ornamented with raised scrollwork.

B represents the door of the ash-pit, ornamented with raised leaflets and scrolls.

C represents the inclined frame of the ash-pit, ornamented with scrolls extending from the top flange down to the base of the frame.

D represents the foot-rails, which are ornamented as a whole with loop and scroll work.

E represents the overhanging flange of the fire-pot. It is ornamented with raised scroll and loop work.

F represents the front of the stove, ornamented with wavy leaflets terminating in scrolls.

G represents the feed-door, ornamented with wavy leaflets terminating at their ends with scrolls.

35

H represents an oval top, ornamented with raised scrolls and loopwork.

Having described my invention, what I claim is—

1. The design for a heating-stove, substantially as herein shown and described. 40

2. The design for the ash-pit door, substantially as herein shown and described.

3. The design for a foot-rest, substantially as herein shown and described. 45

4. The design for the overhanging flange of the fire-pot, substantially as herein shown and described.

5. The design for the upper front of the stove, substantially as herein shown and described. 50

6. The design for the feed-door, substantially as herein shown and described.

7. The design for the top of the heating-stove, substantially as herein shown and described. 55

In testimony whereof I have hereunto set my hand.

STANHOPE BOAL.
